(57) **CLAIM**

The ornamental design for a window or door awning, as shown.

DESCRIPTION

FIG. 1 is a perspective top and right view of a door or window awning showing my new design;

FIG. 2 is a front view thereof;

FIG. 3 is a rear and bottom view thereof;

FIG. 4 is perspective top and right view of a second embodiment thereof;

FIG. 5 is a front view of a second embodiment thereof; and,

FIG. 6 is a rear and bottom view of a second embodiment thereof.

The left side view of the awning is a mirror image of the right side.
